UNITED STATES PATENT OFFICE

2,457,283

TUNGSTEN CARBIDE TOOL GRINDER

Frank P. Slater, Kansas City, Mo.

Application January 14, 1946, Serial No. 641,121

3 Claims. (Cl. 51—125)

1

This invention relates to grinding equipment in general, and particularly to grinders for tungsten carbide tools that are preferably sharpened or contoured through the employment of a grinding element having among other material, diamond chips or dust, and because of which it is desirable to provide a coolant during the grinding operation.

The provision of such a coolant or a liquid serving as such, is a troublesome problem and grinders have heretofore, been rendered expensive and complicated because of efforts to include therein, means for pumping or otherwise forcing a liquid to the zone of juncture between abrading element and tool being ground. It is one of the primary objects of this invention, therefore, to provide a grinder with means for automatically directing a jet of liquid, capable of cooling the frictionally engaged surfaces throughout the entire time that grinding of the tool takes place.

A further important object of this invention is to provide a grinder with an adjustable head, capable of maintaining the tool at an angle where the operator may manipulate the same with the desired amount of pressure toward the abrading surface of a specially mounted cup, having as a part thereof, the means for forcing liquid from the lower part of the reservoir to a place where it will come into contact with the tool.

Other objects of the invention are important and will appear during the course of the following specification, referring to the accompanying drawing, wherein:

Fig. 1 is a top plan view of a grinder for tungsten carbide tools, made in accordance with the present invention; and

Fig. 2 is a vertical central sectional view thereof.

The form of the invention chosen for illustration, comprises a reservoir 10 suitably mounted upon such supports 12 as may be adequate to hold the entire assembly in operative position, and a prime mover in the form of a motor 14, the shaft 16 whereof normally extends vertically.

This shaft 16 passes through a packing 18, capable of precluding seepage or leakage of liquid 20 from within reservoir 10, and the upper end of shaft 16 carries a cup 22, cast or otherwise formed of a strong substance having a facing of abrading material at its edge and against which the later described tool is drawn during operation of the grinder.

Cup 22 has its annular side wall 24 flared or projected upwardly and outwardly from the base 26 of cup 22, and it is the upper, annular edge

of this wall 24 that is brought against the tool. A duct 28 disposed at an angle with respect to the axis of rotation of shaft 16 and cup 22, has its lower end in the lead with respect to the direction of rotation of the cup—thus, as the cup is rotated, liquid 20 will be driven upwardly through duct 28 and be directed toward the inner face of wall 24 adjacent to the annular edge 30 thereof. The supplying of liquid to the frictionally interengaged surfaces of cup 22 and the tool 32, that is being ground, is accomplished by this simple group of parts and so long as the level of liquid 20 remains above the lower end of duct 28, an adequate supply of liquid will be forced against the periphery of cup 22.

The head for holding tool 32 is capable of movement about a vertical axis as well as a substantially horizontal axis, or one that is disposed at right angles to the axis of standard 34.

20 This standard 34 projects upwardly through an opening in the bottom of reservoir 10, and for simplicity of structure, is a continuation of one of the anchoring bolts 36 that serve to hold motor 14 in place. The body of this head is in two sections—one designated by the numeral 38 is rotatably mounted on standard 34 and held in a selected position along the length of said standard by set-screw 40. The other section 42 of this body, is held in position by set-screw 44, and therefore, the tool 32 may be held to have the end thereof ground at an angle suitable to the desires of the operator. This set-screw 44 passes through the section 38 above set-screw 40 and is in screw threaded engagement with section 42 for holding the latter part against section 38. Obviously, these set-screws 40 and 44 may be manipulated after tool 32 is introduced into section 42, and if it is necessary or desirable to maintain tool 32 in place through manual force rather than mechanical, these two set-screws may be left in a loosened condition and such pressure as needed then applied by the hand of the person manipulating the grinder.

45 Cup 22 is removably mounted upon shaft 16 and as wear occurs and renewal becomes necessary, such may be accomplished with ease and dispatch.

50 It will be obvious to one skilled in the art that the head comprising the tool holder, may be set at any desired angle to support tool 32 where it will respond to the touch or grip of the operator as he applies the desired amount of pressure for the grinding action.

55 The coolant will be automatically supplied to the inter-engaging faces of tool 32 and cup 22,

and all driven substances will be confined within reservoir 10 and will not, therefore, create dirt or muss of an objectionable nature.

Reservoir 10 should have its annular, continuous side wall angled inwardly as the top is approached to insure a fulfillment of one of the objects of the invention with respect to cleanliness during the grinding action.

Having thus described the invention, what is claimed as new and desired to be secured by Letters Patent is:

1. In a tool grinder of the character described, a reservoir for liquid coolant; a grinding element rotatably mounted in the reservoir with a portion thereof below the level of the liquid; and means for directing the liquid toward one surface of the element as the element is rotated, said means comprising a duct formed in the element with one end thereof below the surface of the liquid, the said duct being inclined with respect to the axis of rotation of the element and with the said one end of the duct leading the remaining portion thereof as the element is rotated in one direction.

2. In a tool grinder of the character described, a reservoir for liquid coolant; a grinding element rotatably mounted in the reservoir with a portion thereof below the level of the liquid; and means for directing the liquid toward one surface of the element as the element is rotated, said means comprising a duct formed in the element with one end thereof below the surface of the liquid, the said duct being inclined with respect to the axis of rotation of the element and with the said one end of the duct leading the remaining portion thereof as the element is rotated in one direction, said grinding element being cup-shaped and having its annular edge projected upwardly, said

5
10

duct having its ends in communication with the reservoir and the element respectively.

3. A tool grinder of the character described comprising an open top reservoir for liquid; a cup-shaped grinding element in the reservoir having its annular edge projected upwardly; a coating of abrasive on the edge of the said element; a head adjacent the element for holding the tool in operative relation with the said abrasive; and structure for directing a coolant liquid from the reservoir against the abrasive coating as the element is rotated, said reservoir having a closed bottom and an upwardly directed, diverging side wall circumscribing the element and tool holding head, said structure comprising a duct formed in the element with one end thereof below the surface of the liquid, the said duct being inclined with respect to the axis of rotation of the element and with the said one end of the duct leading the remaining portion thereof as the element is rotated in one direction.
